ATTORNEYS.

UNITED STATES PATENT OFFICE.

HENRY S. BLOOD, OF BOTTINEAU, NORTH DAKOTA.

STOVEPIPE-JOINT.

No. 873,859.

Specification of Letters Patent.

Patented Dec. 10, 1907.

Application filed January 24, 1907. Serial No. 353,807.

To all whom it may concern:

Be it known that I, HENRY S. BLOOD, a citizen of the United States, and a resident of Bottineau, in the county of Bottineau and State of North Dakota, have invented certain new and useful Improvements in Stove-pipe-Joints, of which the following is a specification.

My invention is an improvement in stove pipes and similar pipes, and in the particular construction for connecting the meeting ends of the adjoining sections; and the invention consists in certain novel constructions and combinations of parts as will be hereinafter described and claimed.

In the drawing Figure 1 is a side elevation of a pipe joint before being tightened, the flap covering the opening for the introduction of the key being slightly raised. Fig. 2 is a similar view of the joint after it is closed and the flap pressed down to cover the opening. Figs. 3 and 4 are detail side views of the pipe sections detached. Fig. 5 is a vertical longitudinal section of the pipe joint.

In the construction shown the pipe sections A and B telescope at their meeting ends, the section B fitting at one end over the adjoining end of section A and the section A is provided a shortd istance from its extremity a with an annular bead a' which forms a stop to limit the movement of the section A into the section B as will be understood from Figs. 1, 2 and 5 of the drawing.

The section A is provided near its extremity with a groove A² which extends in a spiral direction around the pipe section and the section B has its end which fits over the end of the section A provided with a spiral groove B² of any desired length, the groove in the section A being formed in the outer face of the pipe and the groove in the section B being formed in its inner face and both said grooves being preferably secured by beading the pipe sections in a manner well understood by those skilled in the art. It will be noticed that these grooves when the pipe sections are fitted together, as shown in Fig. 1 coincide, both extending spirally around their respective sections and an opening C is provided leading into the groove B², said opening being secured by slitting the

bead forming the groove B² and also providing a flap C which may be opened as shown in Fig. 1 for the introduction of a key and then closed as shown in Figs. 2 and 4 to cover the opening.

In operation the pipe sections may be telescoped together as shown in Fig. 1 and the flap C being opened the key D may be introduced and pressed around to extend within the spiral channel secured by the grooves A² and B², the channel being preferably of a cross-sectional size slightly in excess of the diameter of the key D so that after the key is introduced to lock the sections A and B together the sections may be turned rotarilly relatively to each other to the position shown in Fig. 2, thus tightening the sections by a screw action, as will be readily understood on reference to the drawing.

The key is preferably a wire of brass, copper or the like not easily corroded. By preference the opening for the insertion of the key is located at the upper end of the spiral.

What I claim is—

1. A pipe joint comprising two telescoped sections the inner one having in its outer face a spiral groove and the outer one having in its inner face a spiral groove coinciding with that in the inner section and an opening leading to the groove in the outer section, and a key extending within the spiral channel formed by the grooves in the inner and outer sections whereby the sections may be fitted longitudinally together, the key introduced and the sections then screwed together to tighten the joint, substantially as set forth.

2. A pipe joint composed of sections telescoped at their meeting ends, one of said sections being provided with a stop to limit the extent to which the sections may telescope and the telescoped portions of the said inner and outer sections being provided with coinciding spiral grooves opening toward each other and forming a channel, and a key in said channel, substantially as set forth.

HENRY S. BLOOD.
